ABSTRACT

The apparatus comprises needle beam means, which carry needle boards, needle beam guide means for vertically guiding said needle beam means, needle beam drive means for imparting an up and down motion to said needle beam means, balancing weight means associated with said needle beam means, balancing weight guide means for vertically guiding said balancing weight means, and balancing weight drive means for imparting to said balancing weight means an up and down motion in phase opposition to said needle beam means.

7 Claims, 2 Drawing Figures

FIG. 1

FIG. 2

NEEDLE PUNCHING APPARATUS

This invention relates to apparatus for needle punching fiber webs or the like, which comprises a needle beam, which may be divided into sections, if desired, and which is vertically guided and is moved up and down by an eccentric shaft through the intermediary of connecting rods, and needle boards mounted in said needle beam.

The web or the like is advanced between a perforated support and an also perforated stripper and as the needle beam is moved up and down the needles of the needle beams pierce into the web or the like from above through the strippers.

In such a needle punching apparatus, relatively large masses are moved up and down and during an operation at a high stroke frequency result in considerable vibration and shakes. It is an object of the invention so to improve the apparatus described first hereinbefore that such vibration and shakes are avoided even during a fast operation of the machine, specifically, of the eccentric shaft for driving the needle beam.

This object is accomplished according to the invention by the provision of a balancing weight associated with the needle beam, or of balancing weights associated with respective needle beam sections, said or each counterweight being also vertically guided and moved up and down in phase opposition to the needle beam. The resulting balancing of masses ensures a smooth running of the overall apparatus. It will be understood that the balancing weight must be matched to the mass of the moving parts of the needle beam.

According to an additional feature of the invention, a particularly desirable design will be obtained if the eccentric shaft is provided between adjacent eccentrics for driving the needle beam with additional eccentrics, which are angularly offset 180° from the first-mentioned eccentrics and act on connecting rods which engage the balancing weight, and the balancing weight is accommodated within a housing, which is known per se and accommodates the eccentrics and connecting rods and forms the shaft bearings and vertical guides, and the balancing weight is preferably guided on rods which are fixed to the housing. In that case the usually existing housing is utilized to accommodate the balancing weight so that the latter does not disturb and does not require additional space for its operation. It will be understood that cranks may be used instead of the eccentrics.

An illustrative embodiment of those parts of a needle-punching apparatus which are essential for the invention are shown by way of example on the accompanying drawing, in which

FIG. 1 illustrates one needle punching unit in a vertical sectional view; and

FIG. 2 illustrates a like view of a plurality of adjacent units.

A drive shaft 1 carries two eccentrics 2 for each beam section, which, by means of connecting rods 3 move two rods 4 up and down. Each needle beam section 5 is suspended from said rods and is provided with needle boards 6. The eccentrics 2 and the connecting rods 3 of each section are accommodated in a housing 7 which forms shaft bearings 8 and vertical guides 9 for the rods 4. When the webs to be needle-punched are wide, a plurality of such units are arranged one beside the other, as shown in the drawing; in that case, the

drive shafts 1 are interconnected by elastic couplings 14.

A balancing weight 11, which is matched to the moving masses of the needle beam section 5, is vertically guided on rods 10, which are secured to the housing. Between the two eccentrics 2, two additional eccentrics 12 are provided, which are angularly offset 180° from the eccentrics 2 and are connected by connecting rods 13 to the balancing weight 11 so that the latter moves up and down in phase opposition to the needle beam during the rotation of the drive shaft 1.

What is claimed is:

1. Needle punching apparatus, which comprises needle beam means carrying needle boards, needle beam guide means for vertically guiding said needle beam means,

needle beam drive means for imparting an up and down motion to said needle beam means, balancing weight means associated with said needle beam means,

balancing weight guide means for vertically guiding said balancing weight means, and balancing weight drive means for imparting to said balancing weight means an up and down motion in phase opposition to said needle beam means.

2. Needle punching apparatus as set forth in claim 1, in which

said needle beam means comprise a single needle beam and said balancing weight means comprise a single balancing weight associated with said needle beam.

3. Needle punching apparatus as set forth in claim 1, in which

said needle beam means comprise a plurality of needle beam sections and said balancing weight means comprise a plurality of balancing weights associated with respective ones of said needle beam sections.

4. Needle punching apparatus as set forth in claim 1, in which

a rotary shaft is provided, said needle beam drive means comprise needle beam drive connecting rod means for converting a rotation of said shaft into an up and down motion of said needle beam means, and

said balancing weight drive means comprise balancing weight drive connecting rod means for converting a rotation of said shaft into an up and down motion of said needle beam means in phase opposition to said needle beam means.

5. Needle punching apparatus as set forth in claim 4, in which

said needle beam drive means comprise axially spaced needle beam drive eccentrics which are carried by said shaft and operatively connected to said needle beam drive connecting rod means and said balancing weight drive eccentrics which are carried by said shaft and disposed between adjacent ones of said needle beam drive eccentrics and angularly spaced 180° therefrom and operatively connected to said balancing weight drive connecting rod means.

6. Needle punching apparatus as set forth in claim 5, which comprises a housing which is formed with bearings for said shaft and with said needle beam guide means and accommodates said needle beam drive eccentrics, said needle beam drive connecting rods, said balancing weight drive eccentrics and said balancing weight drive connecting rods.

7. Needle punching apparatus as set forth in claim 6, in which said balancing weight guide means consist of rods which are secured to said housing.
